FENDER FLAP FOR AUTOMOBILES

Harold Price, Chicago, Ill.

Application March 3, 1955, Serial No. 34,856

Term of patent 3½ years

(Cl. D14—6)

Fig. 1.

Fig. 2.

Fig. 1 is a front view of a fender flap for automobiles showing my new design.

Fig. 2 is an edge view thereof.

The side opposite Fig. 1 is plain.

The characteristic features of my design reside in the large center V in combination with the two oppositely disposed inverted V shapes as shown all in the lower portion of the fender flap.

I claim:

The ornamental design for a fender flap for automobiles, as shown and described.
